Primary Examiner — Rosemary K Tarcza(74) *Attorney, Agent, or Firm* — Feldman Gale, P.A.(57) **CLAIM**

The ornamental design for a charger for a vaporizer, as shown and described.

DESCRIPTION

FIG. 1 is a side perspective view of a charger for a vaporizer with the charger connected to a battery portion for the vaporizer, the battery portion illustrated in broken lines and the cord of the charger illustrated in broken lines;

FIG. 2 is a front perspective view of the charger of FIG. 1; FIG. 3 is a bottom view of the charger of FIG. 1;

FIG. 4 is a front view of the charger of FIG. 1; and,

FIG. 5 is a top view of the charger of FIG. 1.

Features shown in broken lines are for illustrative purposes only and form no part of the claimed design.
